SOUND-PRODUCING TOY

John Pinkney Gowland, Woking, England

Application November 7, 1945, Serial No. 627,131
In Great Britain November 6, 1944

2 Claims. (Cl. 46—99)

1

This invention relates to toys intended to be drawn or propelled on the floor, ground or other running surface, which are adapted to produce sound when in motion. The invention may be embodied in toys of the self-propelled type driven, for example, by a clockwork motor, as well as in toys of the type which are drawn or pushed by hand. The toys may be provided with running wheels, rollers or the like, or may have slide runners or otherwise be adapted to slide on the running surface.

In a toy according to the invention, a simulacrum of any desired character, such as of an animal, bird, insect or other figure, vehicle or craft, conceals a sound producing device of the well-known concertina type employing a weighted bellows, which is rotatably mounted so as to be repeatedly inverted as it rotates, thus causing the bellows alternately to expand and collapse and thereby periodically emit sound, means being provided to drive said device as the toy is moved. The sound producing device is suitably designed to produce sound appropriate to the simulacrum. It is desirable that the sound producing device be rotated at a low speed, and for this purpose the drive thereto may be effected through reduction gear. If the toy has a motor, the sound producing device may be driven therefrom. Alternatively, whether the toy has a motor or not, the sound producing device may be driven from the rotation of a wheel or wheels or the like (or the axle thereof) of the toy as it moves on the running surface. In a further alternative, which is especially suitable for motorless toys with free running wheels, rollers or the like, the sound producing device may be driven from a wheel or roller which contacts with the running surface and operates the drive independently of the running wheels or the like of the toy, and such driving wheel or roller may have a floating mounting so as to ensure that it maintains contact with the running surface.

In order that the invention may be more fully understood and readily carried into practice, an embodiment thereof will be described below in conjunction with the accompanying drawings, in which

Fig. 1 is a side view of one form of sound-producing toy exemplifying the invention.

Figs. 2 and 3 are side and end views respectively, drawn to a larger scale, of the toy with the simulacrum removed to show the sound-producing mechanism.

In the examples shown in the drawings, a simulacrum 10 of any desired character, such as

2

an animal, is made as a hollow figure and mounted on a base board 11 which is adapted to be drawn or pushed along the floor, ground or other running surface, for which purpose the base board 11 may be provided with slide runners or, as shown, with a set of free running wheels 12, which may conveniently be four in number. The sound-producing or "voice" device 13 is of a conventional concertina type employing a weighted bellows 13a and having reeds such as 13b cooperating with orifices such as 13c in an end of the device to produce sound when the bellows is collapsed. The device 13 is carried by a rotatable disc 14 so that as the latter is rotated 5 the "voice" device 13 likewise is rotated and repeatedly inverted as it rotates so as to cause the bellows to alternately expand and collapse and thereby periodically emit sound. The "voice" device 13 may be mounted on the disc 14 by being located in a cut-out slot 15 in the disc and held in position therein by a pair of clips or straps 16, one at each side of the disc 14 and embracing the periphery of the bellows device and secured to the disc 14 as by means of screws 17. 10 The clips 16 are each provided with an outwardly projecting pin 18, the two pins forming stop axles by which the assembly comprising the disc 14 and "voice" device 13 is rotatably mounted between a pair of brackets 19, e. g., of metal strip 15 upstanding from the base board 11, the brackets having vertically elongated bearing slots 20 which receive the axle pins 18. The disc 14 protrudes through a slot 21 in the base board 11 and rests with its periphery on a small intermediate wheel 22 which is fast to and coaxial with a small driving wheel or roller 23 which is adapted to contact and roll along the ground or other running surface as the toy is moved on its wheels 12 along such surface. The roller and disc arrangement 14, 22 and 23, provides a reduction gear drive whereby rotation of the driving wheel or roller 23 imparts a slow-motion rotational drive to disc 14 carrying the "voice" device 13. 20 The common axle 24 of the driving roller 23 and intermediate roller 22 is supported in vertical elongated slots 25 in a pair of spaced brackets 26 depending from the underside of the base board 11. As shown in Fig. 3 the brackets 19 and 26 may be structurally combined and formed by 25 two pieces of metal strip suitably bent as shown and secured, e. g., by screws 27 to the base board 11, each strip having a part upstanding from the base board to form one bracket 19 and a part depending from the underside of the base board to form a bracket 26. By virtue of the

elongated axle slots 20 and 25 in the brackets, the whole drive arrangement comprising rollers 23, 22 and disc 14 carrying the "voice" device 13 can ride up and down or vertically float in the axle slots so as to follow any irregularity of contour of the surface over which roller 23 may run, and the weight of the disc 14 carrying the "voice" device 13 maintains the disc in a frictional driving engagement with the intermediate roller 22 and maintains the driving roller 23 in contact with the running surface. As illustrated in Fig. 1, the chosen hollow figure 10 is secured to the base board 11 so as to cover and conceal the sound-producing mechanism on the top of the base board.

The parts of the described toy may be made as desired in one or more of a variety of materials. For example, the toy made may be chiefly constructed of wood; the base board 11, running wheels 12, disc 13 and drive rollers 22, 23 may be made of this material. The drive parts 23, 22, 14 may have all or some of their peripheries covered with rubber or other suitable friction material to reduce slip. Metal or plastic substances may also be employed as well as different materials for different parts of the toy. The hollow simulacrum 10 may be made of wood or pressed metal or it may be moulded in a plastic or other suitable material, such as moulded pulp, fibre or plaster.

Although one particular form of construction has been described and illustrated, this has been given merely illustratively since the invention is susceptible of wide variation in constructional detail and form as will be evident to those skilled in the art. As will be evident, for example, it may be suitable in some cases to dispense with the reduction gear driving disc 14 and to arrange for that disc to be rotated by direct contact with the running surface, or to arrange for that disc to be driven from one of the running wheels 12 of the toy. It will also be evident that the toy may be assembled and constructed in other ways than that described and illustrated; for instance, it may be constructed without a base board and the hollow simulacrum may itself support the sound-producing device and drive mechanism. While the described embodiment shows a toy to be pulled or pushed on a running surface,

the toy may alternatively be fitted with a conventional clockwork motor and drive as well as with the sound-producing mechanism described which, in that case, may operate as described by obtaining its drive from the roller 23 in contact with the running surface or, alternatively, may be power driven from the motor of the toy.

I claim:

1. A toy comprising a base board fitted with running wheels and having an aperture therein, a pair of spaced bearing brackets fixed to said base and upstanding from the upper side thereof adjacent said aperture, a disc overlying and protruding into said aperture and disposed between said brackets and rotatably supported thereby, said disc having a slot therein, a sound-producing device of concertina type including a weighted bellows located in said slot and secured to said disc so as to be repeatedly inverted as said disc rotates thus causing the bellows alternately to expand and collapse and thereby periodically emit sound, a pair of spaced bearing brackets secured to said base and depending from the underside thereof adjacent said aperture, drive gear between and supported by said depending brackets in driving connection with the portion of said disc protruding through said aperture for rotating the same, said drive gear including a wheel member for engaging the running surface on which said wheels of the toy rest, and a hollow simulacrum mounted on the upper side of said base and enclosing said upstanding brackets, disc and sound-producing device.

2. A toy as defined in claim 1, wherein said upstanding and said depending brackets have vertically elongated bearing slots therein whereby to support said disc and drive means with a degree of vertical float.

JOHN PINKNEY GOWLAND.
